UNITED STATES PATENT OFFICE.

WALTER L. MARR, OF FLINT, MICHIGAN.

CARBURETER.

1,073,695.

Specification of Letters Patent. Patented Sept. 23, 1913.

Application filed March 15, 1913. Serial No. 754,544.

To all whom it may concern:

Be it known that I, WALTER L. MARR, a citizen of the United States of America, residing at Flint, in the county of Genesee and State of Michigan, have invented certain new and useful Improvements in Carbureters, of which the following is a specification, reference being had therein to the accompanying drawings.

- 10 In the construction of carbureters it is desirable that the parts be so disposed as to reduce possibility of leakage in the float chamber and to also check the operation of the valves to prevent battering under the 15 rapid action to which they are subjected when connected with motors running at high speed. It is also desirable that the parts be accessible for ready inspection, repair or replacement.
- 20 This invention relates to a carbureter and to a construction thereof that reduces liability to leakage and cushions the action of the air valve together with an arrangement of the parts which reduces the cost of manufacture and also permits easy renewal or repair of the parts, if necessary.

The invention consists in the matters hereinafter set forth and pointed out in the appended claims.

- 30 The drawing is a view, partially in elevation and partially in longitudinal section, of one form of carbureter that embodies features of the invention.

Referring to the drawing, a casing 1 has 35 a depending tapered hollow portion 2 that terminates in a nipple 3. A jet opening 4 in the upper end of the nipple 3 is controlled by a needle valve closure 5 screwthreaded into the nipple 3 in the usual manner with 40 suitable stuffing box or gland 6 to avoid leakage. An inverted flared or conical vaporizing tube 7 has an upper rim flange 8 seated and secured on a corresponding flange 9 of the casing and a lower beveled 45 flange 10 disposed concentrically to the opening 4 around the upper end of the nipple 3. An air inlet opening 11 is in communication with the interior of the casing through the annular passage around the 50 nipple 3 and through the vaporizing tube 7. An outlet passage or opening in the upper part of the casing is controlled by a throttle valve 12, preferably of the butterfly type, that is operated by a lever 13 or the like. 55 An auxiliary air valve casing 14 is removably secured in an opening in the wall of the

casing 1. An annular valve seat 15 in the upper end thereof is controlled by a closure 16 mounted on a stem 17, reciprocable in the guide opening of a boss 18 of a dash pot 60 cylinder 19 that is adjustably secured in the casing 14. The upper end face of the boss 18 acts as a stop to limit the downward movement of the closure 16 so that the latter correspondingly restricts passage of air 65 through lateral openings in the casing 14 into the main casing 1 between the closure and valve seat 15. A disk 20 secured on the lower end of the stem 17 reciprocates in the dash pot cylinder 19, the latter being closed 70 by a cap 21.

As a matter of good shop practice the dash pot is screwed into the casing 14 and is held in adjusted position by a screw 22 that draws together the slotted wall of the 75 casing 14.

A float feed chamber 30 is removably secured on the nipple 3, preferably against a flange 23 on the latter by means of a collar 24, suitable packing 25 being used to insure 80 a tight joint, while the upper rim 26 is seated against the body of the casing. A suitably disposed float 27 in the chamber is arranged to operate a fuel inlet valve that is housed in a boss 28 at one side of and integral with the float chamber. The float and supply valve do not form *per se* a part of this invention. Suitable openings 29 afford communication between the interior of the float chamber and the jet opening 4. 90

In operation, under slow speed of motor, the air enters the casing and is drawn up through the vaporizing tube around the jet opening in such way as to become thoroughly impregnated with the fuel vapor and have the required richness for starting or slow speed purposes. As the motor to which the carbureter is attached, picks up, the auxiliary air valve automatically admits the proper proportion of air to reduce the mixture to ordinary running proportions. The auxiliary valve is readily regulated to close more or less completely, and the dash pot prevents any battering of the closure or seat. The joint between the float chamber 95 and main casing is above the normal level of liquid in the carbureter chamber, thereby lessening the liability to leakage. All the parts are so disposed that the carbureter 100 may be easily dismounted for inspection or 105 repair.

Obviously, changes, in the details of con-

struction may be made without departing from the spirit of my invention and I do not care to limit myself to any particular form or arrangement of parts.

5. What I claim is:—

1. A carbureter comprising a casing having a depending hollow portion terminating in a jet opening nipple, a vaporizing tube seated in the casing with its lower end portion concentric with the nipple, the casing having an air inlet in communication with the space between the casing wall and the tube, a needle valve controlling the jet opening, a throttle valve controlling an outlet in the casing substantially in alinement with the nipple and tube, an auxiliary air valve casing secured in an opening in the main casing and provided with an annular valve seat at the entrance to the casing and a dash pot cylinder alined therewith, a closure for the annular valve seat, a disk reciprocable in the cylinder, a stem connecting the closure and disk, the dash pot forming a stop for limiting the downward movement of the closure, and a float chamber removable secured on the jet opening nipple and casing.

2. A carbureter comprising a casing having a depending hollow portion terminating in a jet opening nipple, a needle valve closure in the nipple controlling the jet opening, an upwardly flared vaporizing tube secured in an opening in the casing in alinement with the jet opening, the lower end portion of the tube being concentric with the nipple, and the casing having an air inlet opening in communication with the space formed between the wall of the depending hollow portion and the flared tube, a throttle valve controlling an outlet opening in the casing substantially in axial alinement with the tube, an auxiliary air valve casing removably secured in an opening in the main casing and provided with an annular valve seat, a dash pot cylinder longitudinally adjustable in the auxiliary casing, a boss on the cylinder having a guide opening, a closure for the annular valve seat, a stem on the closure reciprocable through the boss, a disk reciprocable in the dash pot cylinder secured to the stem, the boss forming an adjustable stop for limiting the downward movement of the closure, and a float feed chamber sealed against the lower portion of the casing and secured to the depending nipple thereof.

3. A carbureter comprising a main casing having a depending tapered hollow portion terminating in a nipple with a jet opening, a needle closure in the nipple controlling the jet opening, a flared vaporizing tube seated in an opening in the casing op-

posite the jet opening of the nipple with its lower end portion concentric with the opening of the nipple, the casing having an air inlet opening in communication with the space between the wall of the tapered hollow portion and the vaporizing tube, a throttle valve controlling an outlet in the casing substantially in alinement with the vaporizing tube, an auxiliary air valve casing removably secured in an opening in the wall of the casing, a dash pot cylinder adjustably secured in the lower portion of the air valve casing, a cap closing the outer end of the cylinder, a guide boss on the upper end of the cylinder, a valve stem reciprocable therethrough, a disk reciprocable in the cylinder secured to the stem, a valve closure on the upper end of the stem adapted to seal an annular valve seat on the upper end of the auxiliary valve casing, the boss forming an adjustable stop for limiting the movement of the closure, and a float feed chamber secured to the casing on the nipple and around the depending hollow portion.

4. A carbureter comprising a main casing having an integrally formed depending tapered hollow portion, a nipple integrally formed on the lower end thereof, and provided with a jet opening, a needle valve closure, controlling the jet opening, a flared vaporizing tube removably secured at its upper end in an opening in the casing with its lower end portion concentric with the jet opening of the nipple, the casing having an air inlet opening in communication with the space between the wall of the hollow depending portion and the vaporizing tube, a throttle valve controlling an air outlet in the main casing opposite the vaporizing tube, an auxiliary air valve casing removably secured in an opening in the main casing, a dash pot cylinder longitudinally adjustable in the lower end portion of the auxiliary casing, a guiding boss on the upper end portion of the cylinder, a cap closing the lower end of the cylinder, a stem longitudinally reciprocable through a guide opening in the boss, a disk reciprocable in the cylinder secured to the stem, a closure secured to the stem for an annular valve seat on the upper end of the auxiliary casing, the boss forming a stop for limiting the movement of the closure, and a float chamber secured at its lower end to the depending nipple of the main casing with its upper marginal portion abutting the main casing.

In testimony whereof I affix my signature in presence of two witnesses.

WALTER L. MARR.
